(57) **CLAIM**

The ornamental design for a pillar lantern ring with a brace, as shown and described.

DESCRIPTION

FIG. 1 is a top front perspective view of a pillar lantern ring with a brace showing my new design; a top rear perspective view; a bottom front and a bottom rear perspective views being identical;

FIG. 2 is a top plan view thereof, and a bottom plan view being identical;

FIG. 3 is a left side elevational view thereof, and a right elevational view thereof being identical;

FIG. 4 is a front elevational view thereof, and a rear elevational view thereof being identical; and,

FIG. 5 is a top perspective view of the pillar lantern ring with a brace split showing the two halves thereof.
